UNITED STATES PATENT OFFICE.

CLARENCE A. FULLERTON, OF NEW YORK, N. Y.

DEAL-PLATE.

1,251,997.

Specification of Letters Patent.

Patented Jan. 1, 1918.

Application filed June 28, 1916. Serial No. 106,516.

To all whom it may concern:

Be it known that I, CLARENCE A. FULLERTON, a citizen of the United States, residing at New York, in the county of New York and State of New York, have invented certain new and useful Improvements in Deal-Plates; and I do hereby declare the following to be a full, clear, and exact description of the invention, such as will enable others skilled in the art to which it appertains to make and use the same.

This invention relates to banking equipments and more particularly to the plate in the wall of a teller's cage over which monetary transactions are had.

It has for an object to provide an improved type of support, for such a plate, to permit said plate being swung from a normal position to close the opening over said plate when so desired.

Further objects are the provision of a card holding frame to permit the teller's name or identification being displayed, and the invention also provides for the arrangement of links which serve to hold the plate in raised position.

Further objects will be apparent from the following specification, appended claims and drawings, in which,

Figure 1 is a plan view of a plate herein-after termed the deal plate, showing parts thereof broken away;

Fig. 2 is a front elevation of a portion of the cage showing the plate carried therein, and

Fig. 3 is a vertical sectional view through parts of the device showing some of said parts in elevation.

In banking institutions, where they have a number of tellers, it frequently occurs that it is desirous of having the deal plate so mounted as to serve as a deal plate when the teller is present in his cage and to further provide that the deal plate may be tilted or swung to close the opening through which any transactions occur when the teller is absent from his cage and it is also customary to provide an identification as well as a notification to depositors or the like, when the teller in any booth is absent.

This invention provides for the mounting of a deal plate in a swinging frame having locking means for holding said deal plate in either of its adjusted positions and referring to the drawings, in which the several parts are shown, 10 indicates the wall

of the teller's cage which wall is cut away as at 11 to receive the swinging frame 12 in the cut-away portion. The wall 10 supports a trunnion 13 on each end, which supports each end of the frame 12 as shown. The frame 12 has a pocket 14 formed therein and said frame has an opening 15 in the upper wall thereof to permit a card inserted in said pocket being displayed through the opening 15. The frame 12 supports the cushions 16 along the sides 17 thereof, and these cushions receive a plate of glass or other transparent material 18, which may have the major portion of the under surface 60 frosted or otherwise rendered opaque as shown at 19, leaving a clear space 20 centrally therein, to overlie the opening 15. This permits a name plate 21 inserted in the pocket 14 being displayed through the glass 65 deal plate 18.

The frame 12 has extensions 22 at each end thereof, and these extensions terminate in the upwardly extending ears 23 in which are placed screws 24 to engage with rubber 70 or similar cushions 25 in the sockets 26 formed in the edges of the plate 18. This provides for properly attaching the plate 18 to the frame 12.

The rear strips 17 of the frame 12 are 85 notched as at 27 to permit the name plate 21 being inserted in or removed from the pocket 14.

One of the extensions 22 has ears 28 secured thereto, between which a latch 29 is 90 pivotally mounted and this latch has a nose 30 to engage under a trip 31 formed on the frame 32 carried by the rear wall 33 which is stationary and co-operates with the frame 10 in forming the wall of the cage.

A bracket 34 is attached to the rear wall 33 and this bracket carries a bearing plate 35 upon the upper face of which is attached a buffer 36.

When the deal plate 18 is swung to the 100 position shown in dotted lines in Fig. 3 so as to close the opening 37 through which monetary transactions occur, the link 38 pivotally carried by the frame 32 and the link 39 pivotally carried by the frame 12, 105 swing to and slightly beyond the straight line when the lugs 40 and 41 formed on the links 38 and 39 engage each other to limit further movement thereof. The links 38 and 39 are pivotally secured to each other 110 and the opposite ends thereof, are pivotally secured between ears 42 on the frame 32 and

43 on the frame 12. When it is desired to lower the plate for usage, the rear edge of said plate may be slightly raised to cause the links 38 and 39 to assume a straight line and 5 then by a slight pressure on an extension 44, the knuckle or joint of the links 38 and 39 may be pushed forward, after which said plate may be lowered to permit the latch 29 to lock the plate in the lower position. This 10 latch may be normally held in a forward position as by the spring 45 and it is apparent that said latch will hold the deal plate in locked position for usage until said latch is manually released.

15 It is thought that the use and operation of the deal plate is sufficiently described in the foregoing and it is also apparent that modifications may be made in view of the forms shown in the drawings herewith 20 which are for illustrative purposes only.

Having thus described this invention, I claim:—

1. In a deal plate, a wall having an opening therein, a frame pivotally carried by 25 said wall, a pocket formed in said frame to receive a display card and a transparent plate having portions thereof rendered opaque carried by said swinging frame.
2. In a deal plate, a wall having an opening therein, trunnions carried by said wall, a frame pivotally carried by said trunnions, said frame having a pocket formed therein to receive a display card, a plate carried by said frame, said plate having portions there- 35 of transparent to expose the display card, extensions from said frame for engaging and holding said plate to said frame and means for holding said frame and plate in an inclined position to expose the display card.
3. In a deal plate, a wall having an opening therein, a frame pivotally mounted in said wall, said frame having a pocket formed therein to receive a display card or name 40 plate, cushions carried by said frame, ex- 45 tensions from said frame, a plate carried by

said frame on said cushions between said extensions, said plate having a transparent portion overlying the name plate carried by the pocket in said frame, a latch carried by said frame for holding said frame in a 50 locked lower position and links carried by said frame and said wall for holding said frame and plate in an inclined position to display the name plate.

4. In a deal plate, a wall having an opening therein, a frame pivotally mounted in said opening, said frame having a pocket formed therein, a name plate interchangeably inserted in said pocket, extensions from said frame, ears rising from said extensions, 55 a plate carried by said frame between said ears, said plate being recessed between said ears, screws carried by said ears engaging in said recessed portion of said plate, a spring pressed latch member carried by one 60 of said extensions, said latch coacting with the projection carried by said wall to lock said frame in its lower position and links carried by said wall and said swinging frame having a limited movement in one direction, serving to maintain said frame and plate in an inclined position in one position of said links and said links permitting the lowering of said frame by a forward motion of the knuckle of said links. 70

5. In a deal plate, a wall having an opening therein, a frame pivotally mounted at the lower portion of said opening, said pivotal mounting being in advance of the center of gravity of said frame, a plate carried by 80 said frame, and means carried by said wall and frame for holding said frame in inclined position to close said opening by said plate.

In testimony whereof I affix my signature in presence of two witnesses.

CLARENCE A. FULLERTON.
